MULTI-FUNCTIONING MOLDED PULP ARTICLE-PACKING MEMBER

Charles J. Chaplin, South Portland, Maine, assignor to Diamond National Corporation, New York, N.Y., a corporation of Delaware

Filed Feb. 25, 1960, Ser. No. 11,017
3 Claims. (Cl. 206—46)

The present invention relates generally to molded pulp articles and more particularly to a molded pulp article packing member which is adapted to be used to substantially suspend an article in a protected condition in a packing carton.

Molded pulp packing members known heretofore have been used in pairs on symmetrically formed articles to protect the same in a rectangular packing carton. However, in these instances, the similar portions of the packing member were disposed on similar portions of the article being protected. Thus, if the article was not symmetrically formed, i.e., had a different configuration at opposite ends, it was necessary to design two different packing members for such differently conformed opposite ends.

A primary object of the invention is to provide a dual functioning packing member especially suitable for packing sensitive electrical meters and the like, in which a single packing member includes two different protecting portions engageable with differently conformed ends of the article being supported and thus eliminating the necessity for designing more than one packing member to protect the different ends of the article.

Another object of the invention in conformance with that set forth is to provide a packing member which will effectively protect sensitive instruments from damage due to shocks and vibrations encountered in transit.

A still further object of the invention is to provide a novel and improved packing member which is economical in manufacture, reliable in use, and which is readily accommodated on the article being protected and in the packing carton in which the article is to be packed.

The above, as well as additional objects of the present invention, will be more clearly understood from the following description of a preferred embodiment of the novel packing member, reference being made to the accompanying drawings wherein:

FIGURE 1 is an exploded perspective view of a pair of the novel molded packing members showing them oriented in a position to be disposed on the upper and lower ends of an electrical meter;

FIGURE 2 is a side elevation of a package formed by using the members of FIGURE 1, showing these members disposed in a rectangular packing carton which is broken away and shown in section;

FIGURE 3 is an enlarged horizontal section taken substantially on line 3—3 of FIGURE 2;

FIGURE 4 is an enlarged vertical section taken substantially on line 4—4 of FIGURE 2;

FIGURE 5 is an enlarged top plan view of a novel packing member in its unfolded condition;

FIGURE 6 is a section taken on line 6—6 of FIGURE 5; and

FIGURE 7 is a fragmentary bottom plan view of a portion of the packing member.

The novel packing member will be readily manufactured by known molded pulp techniques from a slurry of pulp fibers. The specific details of such manufacture form no part of the present invention, but reference can be made to United States Letters Patent 2,585,049 and 2,192,937 for disclosure of manufacturing techniques.

Referring to the drawings in detail, and especially FIGURES 5—7, the molded pulp packing member of the in-

2

vention, as will become apparent, is symmetrical about its vertical and horizontal axis. Thus, a description of the central portion of the packing member in relation to one of its sides would appear to be sufficient for the purposes of describing the invention.

Referring to FIGURE 5, the molded pulp packing member is indicated generally at 10 and includes a rectangular or square center section 12 defined by peripheral hinge lines 14 which hingedly connect the central section to side sections 16, 18, 20 and 22. It will be noted that the side edges of the side sections 16—22 are cut inwardly into the center section 12 as indicated at 24 in order to provide a space therebetween when the packing member is disposed about an article. Extending from the side 26 of the packing member is an annular collar 28 which forms a recess or cut-out portion 30 including an annular inwardly disposed abutment shoulder 32. The side 26 may be considered to be the general plane of the packing member.

The other side 34 of the packing member includes an annular orienting collar 36 disposed inwardly of the fold lines 14. Rectangularly disposed at each of the corners of the center section 12 are triangular shaped abutment portions 38 extending out of the surface 34 and having an arcuate side 40 spaced inwardly of the orienting shoulder 36 and an abutment surface 42 which will engage upon a portion of the meter as will subsequently become apparent. Each of the side sections 16—22 has, extending from the surface 34 at the hinge lines 14, when at right angles thereto, an abutment-foot portion 44, the lower surface 46 of which merging or extending into the hinge line and the upper surface 48 thereof forming a shoulder which will be coplanar with the upper surfaces 42 of the abutments 38 when the sides are folded at the hinge lines 14 at substantially right angles to the central section 12 and the surfaces 46 engage the orienting shoulder or ring portion 36.

Extending out of the surface 34, on opposite sides of and outwardly spaced from the abutment-feet 44 are positioning ribs 50 which include an arcuate side portion 52, an angular side portion 54 and a shoulder portion 56, the shoulder portion 56 overlying the abutment surfaces 42 when the sides are folded at 90° or normal to the central section 14. The ribs 50 form at the edges 58 thereof support feet indicated at 60 in FIGURE 1 for engaging the bottom of surface of the carton in which a meter is packed.

Considering FIGURE 1, an electrical meter M includes a cylindrical case 60' having a circular mounting plate 62 at one end from which project a plurality of screws 64. Included at the other end of the case 60' is a rectangular flange 66 having depending from each of the corners and extending along the side of the casing 60, mounting studs 68, the cover of the meter including a raised glass face 70 overlying the indicating dial of the same.

Considering FIGURES 1 and 2, side sections 16—22 will be folded along the fold lines 14 to the position shown in the lower portions of FIGURES 1 and 2. The mounting plate 62 will be received within the recess 30 of the annular collar 28 and will rest upon the annular shoulder 32; this detail is also clearly shown in FIGURE 4. It will be noted when the packing member is disposed in this position, the portion 46 of the abutment foot 44 will engage the orienting ring 36 orienting the side sections substantially normal to or at right angles to the central section 12. A rectangular carton C will engage the feet 60 of the member 10, see FIGURE 4, and thus the meter M will be suspended or supported above the bottom of packing carton. A second packing member indicated at 10' in FIGURES 1—4, will be disposed in overlying relationship to the rectangular flange 66 of the

meter. The glass face 70 will be disposed within the annular orienting ring 36, the abutment-feet 44 will orient the side sections at substantially 90° to the central section 12 and the shoulder portions 48 of the abutment feet will be substantially coplanar with the upper surface 42 of the abutment portions 38 which are at each of the corners of the central section 12 of the packing member. When the sides 16-22 are folded inwardly onto the rectangular flange 66 of the meter, the arcuate surface portions 52 of the positioning ribs 50 will engage the cylindrical outer surface of the casing 60. At the same time, the shoulder portions 56 of the positioning rib will engage the undersurface of the rectangular flange 66 of the meter, see FIGURE 4.

As seen in FIGURE 3, the angular sides 54 of adjacent ribs 52 will extend on opposite sides of the studs 68 of the meter, and these angular sides 54 terminate in angular end portions 72, which will abuttingly engage the inner surface of the carton C.

If an excessive force should be imposed on one of the sides, adjacent the corner of the carton C, the space 74 between adjacent portions of the positioning ribs will permit the packing member to yield and form a circular protecting element around the casing 60' of the meter.

In view of the foregoing, it will be noted that opposite side portions of the meter packing member will accommodate one end of the meter on one side and the other end of the meter on its opposite side.

The meter will be yieldably suspended within the packing carton C and various shocks or vibrations which occur during transit will be absorbed by the yieldable packing member and not be transmitted to the meter.

Although it has not been disclosed in detail, if desired, a suitable reinforcing strap 89 as shown in phantom lines on FIGURE 5, may be utilized for providing additional reinforcement to the recess 30, such a strip extending chordally across this recess.

It will be obvious to those skilled in the art that various changes may be made without departing from the spirit of the invention and therefore the invention is not limited to what is shown in the drawings and described in the specification, but only as indicated by the scope of the appended claims.

What is claimed:

1. In a package comprising a rectangular container, an article comprising a cylindrical casing including differently conformed opposite ends, one of said casing ends including a rectangular flange surrounding a transverse lens portion, mounting studs projecting from one side of said rectangular flange at the corners thereof and parallel to the outer surface of said casing, the other casing end including mounting screws projecting longitudinally therefrom, and a pair of identically conformed packing members disposed in respective inverted relationship at opposite ends of said casing and within said rectangular container, said packing members comprising a transversely apertured rectangular center section, four

rectangularly disposed side sections uni-directionally hinged at right angles with respect to adjacent side sections of said center section in juxtaposition with the inner surface portions of said rectangular container, said rectangular center section including on one side thereof a circular recess portion extending in the direction toward which said side sections are uni-directionally hinged and circumscribed about one end of the cylindrical casing, the other side of said rectangular center section including rectangularly disposed abutment portions engaging beneath the respective corners of said rectangular flange of the cylindrical casing, said circular recess portion including a circular orienting portion disposed inwardly of said rectangularly disposed abutment portions, said side sections of said packing members including abutment foot-portions adjacent said hinge line and positioning said side sections normal to said rectangular center section, said abutment foot-portions including a shoulder portion in substantially coplanar relation and providing a fragmentary support surface at one side of said rectangular flange, said packing member side sections including positioning ribs extending in the direction of said abutment foot-portions and including a first surface portion spaced from and substantially parallel to said shoulder portions and positioned in overlying relationship to said abutment portions, said positioning ribs including second surface portions substantially normal to said first surface portions and arcuately conformed and juxtaposed on a fragmentary portion of the outer surface of said cylindrical casing, said positioning ribs including angularly extending portions diverging away from one edge of said second surface portions, said angularly extending portions forming a space therebetween in which the mounting studs of said rectangular flange are received.

2. The structure of claim 1, said shoulder and first surface portions together with adjacent side sections forming a segmental rectangular recess in which the corners of said rectangular flange of said casing are received and supported.

3. The structure of claim 1, said circular recess including a peripheral rib extending out of the plane of said center section and circumscribed about one end of said casing, said orienting portions comprising a circular rib positioned inwardly of said abutment portions and in engagement with one end of said cylindrical casing.
